UNITED STATES PATENT OFFICE

118,689

DESIGN FOR A SUPPORT FOR DISPLAYING PHOTOGRAPHS, CARDS, AND SIMILAR ARTICLES

Myron J. Zimmer, Chicago, Ill., assignor to The Edward Katzinger Company, Chicago, Ill., a corporation of Illinois

Application September 25, 1939, Serial No. 87,380
In Great Britain June 15, 1939

Term of patent 7 years

To all whom it may concern:

Be it known that I, Myron J. Zimmer, a citizen of the United States, residing at Chicago, in the county of Cook and State of Illinois, have invented a new, original, and ornamental Design for a Support for Displaying Photographs, Cards, and Similar Articles, of which the following is a specification, reference being had to the accompanying drawing, forming a part thereof.

Fig. 1 is a perspective view of a support for displaying photographs, cards, and similar articles, showing my new design;

Fig. 2 is an end elevational view of Fig. 1; and
Fig. 3 is a bottom plan view.

I claim:

The ornamental design for a support for displaying photographs, cards, and similar articles,
as shown.

MYRON J. ZIMMER.
